CLAIM

The ornamental design for a bottle, as shown and described.

DESCRIPTION

FIG. 1 is a front elevational view of a bottle embodying my new design, the rear elevational view being a mirror image thereof;

FIG. 2 is a left side elevational view of the bottle;

FIG. 3 is a right side elevational view of the bottle;

FIG. 4 is a top plan view thereof;

FIG. 5 is a bottom plan view thereof;

FIG. 6 is a fragmentary view looking in the direction of the arrows designated 6—6 in FIG. 1; and

FIG. 7 is a fragmentary view looking in the direction of the arrows designated 7—7 in FIG. 1.
